UNITED STATES PATENT OFFICE

159,916

SLIDE VIEWER

Herman F. Miller, Los Angeles, Calif.

Application July 16, 1949, Serial No. 3,960

Term of patent 7 years

(Cl. D61—1)

To all whom it may concern:

Be it known that I, Herman F. Miller, a citizen of the United States, residing at Los Angeles, in the county of Los Angeles and State of California, have invented a new, original, and ornamental Design for a Slide Viewer, of which the following is a specification, reference being had to the accompanying drawing, forming part thereof.

In the drawing

Fig. 1 is a front perspective view of the slide viewer showing my new design;

Fig. 2 is a side elevation of the slide viewer,

Fig. 3 is a rear elevation of the slide viewer, and

Fig. 4 is a top plan view thereof.

I claim:

The ornamental design for a slide viewer, as shown.

HERMAN F. MILLER.
